UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEWING-MACHINE BRAIDER.

1,185,778.

Specification of Letters Patent.

Patented June 6, 1916.

Application filed August 24, 1914. Serial No. 858,170.

To all whom it may concern:

Be it known that I, ALBERT H. DE VOE, a citizen of the United States, residing at Westfield, in the county of Union and State 5 of New Jersey, have invented certain new and useful Improvements in Sewing-Machine Braiders, of which the following is a specification, reference being had therein to the accompanying drawings.

10 This invention has for its object to provide a sewing machine braid-guide through which the braid is led from the rear of the stitch-forming devices to receive stitching passing entirely through the same and into 15 the body fabric, thereby exposing the stitching devices unobstructedly to the operator and thus facilitating the handling of the work.

As preferably constructed, the braider 20 comprises a presser-foot having in its pressure member laterally spaced needle-apertures embraced by a braid-delivery guide-channel in the forward part of the under face thereof, a taper leading-in guide-tube 25 of inverted U-shape being extended from the rear through the presser-foot shank and directed between said needle-apertures on the upper face of the pressure member. The forward extremity of the pressure member is 30 preferably transversely notched to afford a braid-turning edge intermediate the upper leading-in guide and the lower guide-channel, and adjacent such notch the pressure member has upon its upper face an arched 35 and wedge-shaped projection for spreading or distending the braid or tape leading from the upper guide to the lower channel in advance of the needle-apertures. By this means, a braid may be led in laterally contracted form between the needles and distended to its full width in advance of the latter so as to pass beneath the same through the guide-channel of the presser-foot to receive lines of stitching along the opposite 40 margins in the laying of the braid upon a body fabric in ornamental patterns. It is evident that the present improvement is applicable to machines employing only a single needle, the upper leading-in guide being 45 properly formed and disposed to direct the braid wholly to one side of the needle, and that the presser-foot is not a necessary part of the attachment, although desirable.

The invention will be understood by reference to the accompanying drawings, in 55 which—

Figure 1 is a perspective view of a portion of a sewing machine provided with the present improvement, Fig. 2 is a sectional side elevation of the attachment upon a larger 60 scale, and Fig. 3 a plan of the same. Figs. 4 and 5 are perspective views of the attachment, taken from different positions, and Fig. 6 is a front end elevation thereof.

As represented in the drawings, the present improvement is embodied in a sewing machine presser-foot comprising the shank 1 of usual form and the foot-plate or pressure member 2 provided in the present instance with the laterally spaced needle-apertures 3 and formed in its under face forwardly of and embracing said needle-apertures with the downwardly and backwardly inclined braid-delivery guide-channel 4 leading from a transverse notch in the forward extremity of the foot-plate affording 75 a braid turning edge 5 around which the braid is led from the upper face of the pressure member between the forwardly extending toes 6.

The presser-foot shank 1 is apertured adjacent the member 2 to receive the taper leading-in braid-guiding tube 7 of U-shaped cross-section directed between the needle-apertures 3 and toward the braid-turning 85 edge 5, the contracted mouth of such tube having a width corresponding substantially with the spacing apart of the needle-apertures, while the flared backwardly extending portion terminates rearward of the 90 presser-foot shank in an upwardly inclined lip 8 beneath which the braid is led from the source of supply into the guide-tube.

As represented in the drawings, the central member 7' of the guide-tube, which is 95 U-shaped at the rearward extremity, extends forwardly and merges at the opposite end into a flat blade or fin 7''. The top of the pressure-plate 2 affords a bottom for the forward portion of the guide-tube 7 which 100 latter is formed in its upper side with the slip 9 for inspection and access to the braid for adjustment by a stiletto or other instrument.

The top of the pressure member 2 has intermediate the mouth of the guide-tube 7

and the braid-turning edge 5 a pyramidal braid-spreading projection 10 having a triangular base with one side coincident with the edge 5 and the opposite angle directed intermediate the needle-apertures and toward the guide-tube 7. The said angle of the base of the spreading projection enters the standing fold of the braid or tape as it issues from the guide-tube between the 5 needle-apertures and the wedge-shaped spreader afforded by said projection serves to distend the edges of the tape to facilitate the flattening of the same as it is drawn around the braid-turning edge 5 and advances from the same through the channel 10 15 4 beneath the presser-foot.

The presser-foot shank has the usual lateral slot 1' entered by the fastening screw 11 by which said shank is attached to the 20 presser-bar 12 journaled in the head 13 of the sewing machine bracket-arm in which is journaled the reciprocating needle-bar carrying the needle-clamp 14 provided with the laterally spaced needles 15 which coöperate 25 in practice with suitable loop-taking means beneath the bed-plate 16.

As represented in Fig. 1, the braid 3 is folded into flattened tubular form and is led from the source of supply rearward of the 30 sewing machine bracket-arm downwardly beneath the tongue 8 and through the guide-tube 7, over the spreader 10 and turning edge 5 and thence backwardly through the lower channel 4 beneath the needle-apertures 3 35 and across the paths of movement of the needles. The braid having been inserted as described while the presser-foot was raised, a body fabric *m* is introduced beneath the presser-foot and the latter is lowered and 40 the stitching proceeded with in the usual manner, the body fabric being turned as required to produce the desired ornamental figure or pattern of the braid thereon.

In applying a braid made from a bias 45 tape, the edge 5 over which the braid is turned may be disposed at a right angle with the direction of feed for laying the braid in a curved pattern, such as that represented in Fig. 1, the longitudinally yielding 50 character of the braid causing it to adjust itself to the face of the body fabric without puckering; but with a braid of which the warp threads run lengthwise thereof, longitudinal elasticity is lacking and there is less 55 adaptability of the braid to such condition. To facilitate the proper laying of such braid in a curved pattern, the turning edge 5 may be made slightly inclined, as represented in the drawings, so that the braid running taut 60 over said edge is thereby crowded slightly to one side against the adjacent guide-toe 6 and toward the center of curvature of the pattern, the outer edge being tightened while the inner edge is slackened in tension, 65 thereby insuring smoothness in the lay of

the braid upon the body fabric upon which it is secured by the marginal lines of stitching *s*.

It is evident that the specific character of the braid-delivery guide through which the 70 braid passes to the stitch-forming and feeding mechanisms is not material to the present invention, as the braid would be effectively positioned for certain classes of work by provision either of a guiding channel 4 in 75 the lower face of the presser-foot or the notch embraced by the forwardly projecting toes 6; but the braid-delivery guide preferably includes both of these elements for confining the braid to a fixed path of movement 80 in its presentation for the stitching operation.

An important and distinguishing feature of the present improvement is the superposed leading-in guide in conjunction with the braid-delivery channel designed to lead the braid from a point rearward of the stitching mechanism and out of the range of action of the latter to a point in advance thereof from which it is directed within the 90 range of action of the stitch-forming mechanism for attachment to the body fabric. It is evident that the improvement is therefore susceptible of very material variation from the present embodiment without departure from the scope of the present invention.

Having thus set forth the nature of the invention, what I claim herein is:—

1. A sewing machine attachment comprising a presser-foot having a needle-aperture and a braid-delivery guide in advance thereof, and a leading-in guide for the braid extending forwardly from the rear of said presser-foot and directed to one side of said needle-aperture and toward said delivery guide, said leading-in guide being of less width adjacent the needle-aperture than the delivery guide.

2. A sewing machine attachment comprising a presser-foot having laterally spaced needle-apertures and a braid-delivery guide in advance thereof, and a leading-in guide for the braid extending forwardly from the rear of said presser-foot and directed intermediate said needle-apertures and toward said delivery guide.

3. A sewing machine attachment comprising a presser-foot having laterally spaced needle-apertures and a braid-delivery guide in advance thereof, and a leading-in guide for the braid of transversely arched form extending forwardly from the rear of said presser-foot and directed intermediate said needle-apertures and toward said delivery guide.

4. A sewing machine attachment comprising a presser-foot constructed with a shank and a pressure member having a needle-aperture and a braid-delivery guide-channel

in its lower face, and a tubular leading-in guide extending through the presser-foot shank above said channel and at one side of the needle-aperture.

5. A sewing machine attachment comprising a presser-foot having a needle-aperture and a braid-delivery guide with a transverse braid-turning edge at its forward extremity and in advance of said needle-aperture, and

10 a leading-in guide for the braid of transversely arched form extending forwardly from the rear of said presser-foot and directed to one side of said needle-aperture and toward said braid-turning edge.

15 6. A sewing machine attachment comprising a presser-foot having a needle-aperture and a braid-delivery guide with a transverse inclined braid-turning edge at its forward extremity and in advance of said needle-aperture, and a leading-in guide for the braid of transversely arched form extending forwardly from the rear of said presser-foot and directed to one side of said needle-aperture and toward said braid-turning

25 edge.

7. A sewing machine attachment comprising a presser-foot having a needle-aperture and a braid-delivery guide in advance thereof, a leading-in guide for the braid extending forwardly from the rear of said presser-foot and directed to one side of said needle-aperture and toward said delivery guide, and a braid-spreading element disposed intermediate said guides.

30 35 8. A sewing machine attachment comprising a presser-foot having a needle-aperture and a braid-delivery guide with a transverse braid-turning edge at its forward extremity

and in advance of said needle-aperture, a leading-in guide for the braid of transversely arched form extending forwardly from the rear of said presser-foot and directed to one side of said needle-aperture and toward said braid-turning edge, and a braid-spreading element disposed intermediate 40 45 said braid-turning edge and the needle-aperture.

9. A sewing machine braider comprising a braid-delivery guide including a braid-turning element and a superposed leading- 50 in guide for the braid having a width in a portion thereof which is less than that of said delivery guide.

10. A sewing machine braider comprising a braid-delivery guide including a braid- 55 turning element, a superposed leading-in guide for the braid having a width in a portion thereof which is less than that of said delivery guide, and a braid-spreading element disposed in alinement with said leading-in guide and intermediate the same and the braid-delivery guide.

11. A sewing machine braider comprising a braid-delivery guide-channel having a flat operative face, and an oppositely directed 60 and superposed tubular leading-in guide of arched cross-section of a width at the end adjacent said delivery guide less than that of the latter.

In testimony whereof, I have signed my 70 name to this specification, in the presence of two subscribing witnesses.

ALBERT H. DE VOE.
